BREAD AND BUTTER SAUCER OR ARTICLE OF SIMILAR NATURE

Albert J. Dreitzer, New York, N. Y., assignor to Pitman-Dreitzer & Co., Inc., New York, N. Y., a corporation of New York

Application September 22, 1948, Serial No. 148,704

Term of patent 14 years

(Cl. D36—2)

To all whom it may concern:

Be it known that I, Albert J. Dreitzer, a citizen of the United States of America, and a resident of New York, in the county of New York and State of New York, have invented a new, original, and ornamental Design for a Bread and Butter Saucer or Article of Similar Nature, of which the following is the specification, reference being had to the accompanying drawing, forming a part hereof:

Figure 1 is a top plan view of a bread and butter saucer or article of similar nature, showing my new design.

I claim:

The ornamental design for a bread and butter saucer or article of similar nature, substantially as shown.

ALBERT J. DREITZER.
